FORMING OF WELTS IN STRAIGHT KNITTING MACHINES

Alfred Hofmann, Palisade, and Friedrich Max Wachtler, West New York, N. J., assignors to Alfred Hofmann, Inc., West New York, N. J., a corporation of New Jersey

Application February 23, 1939, Serial No. 257,772

67 Claims. (Cl. 66—96)

This invention relates to the forming of welts in straight knitting machines, of the kind having a united bank of needles. The improvement has particular reference to the flat knitting of full-fashioned stockings wherein, after hooking-up the first course or courses, a predetermined length of fabric is knitted at the top of the leg, several inches in extent, which is then turned or folded back and, during a pause in knitting or between the laying of courses, has its initial loops looped back again upon the needles so as to be incorporated in the next knitted course, the fabric being thus formed into a double fabric or welt, the first and last courses of which both become locked with the loops of the next succeeding course. The invention includes the method to be described and the means and mechanism for carrying it out.

It is well known practice in the hosiery art to effect the formation of the welt, that is, the initial hooking-up and the later transfer, through the manual manipulation of a bank or bar of welt hooks, first for the hooking-up and then to turn back the welt fabric or web and loop it upon the needles. The row of welt hooks or loop holding and transferring implements is usually mounted in the welt bar with spacing corresponding to that of the bank or series of main needles. The needles usually have spring beards and are mounted unitedly in a needle bar or bed, and with them cooperate other usual knitting elements or instruments, including series of web-holders or sinkers, and knockovers or bits. The present invention pertains more particularly to the mode of cooperation of the welt forming implement or bank of hooks with the needles and needle-cooperating elements, and to the mechanism for assisting or effecting such cooperation, which may be partly manual or semi-automatic, but is preferably substantially automatic, in receiving initially one or more of the initial loop courses, holding the loops during knitting of the welt, and subsequently restoring such initial loops back upon the respective needles.

In the standard prevailing types of flat knitting machines certain methods and means have been proposed for the mounting and mechanical operation of the welt bar. Substantial difficulties have not been satisfactorily met in the welt forming operations, the taking of the initial loops and transferring the loops back from the hooks to the spring beard needles. The cooperative movements of the welt hooks and needles require great exactitude, absence of which may be the cause of failure of operation, or of damage. Further

difficulty is presented in the accurate manipulation of the welt hooks for their extraction or disengagement from the transferred loops. One plan involves the slight shifting or side-stepping of the welt bar so that the hooks may operate between the needles for the initial reception of loops but each in the plane of its needle during the loop transferring operations. This slight shifting movement has presented problems in performing it with the necessary exactness, especially in a multiple section knitting machine, the slightest inaccuracies tending not only to impair the operations but to cause clash and frequent injury to the instruments.

The general object of the present invention is to render automatically exact and reliable the several movements of the welt bar and its bank of hooks relatively to the needles and other instruments, and to provide proper fittings for the welt bar to allow such movements, and operating connections for putting it through the movements. Other objects and advantages will be explained in the following description of an illustrative embodiment of the invention or will be understood by those conversant with the subject.

Terms of direction or location are used herein in a relative sense for purposes of description and are not intended as limitations upon the essential character of the invention. Further, the terms longitudinal and lateral, to avoid confusion, will be used generally in the sense of the direction in which the knitting progresses, in each section, this to be considered as longitudinal, so that the length of the needle bar, welt bar etc. is transverse or lateral thereto.

In the accompanying drawings, Fig. 1 is a general right hand elevation of a full fashioned stocking knitting machine embodying the present invention, the knitting instruments in small scale being shown conventionally and in an initial or idle position or stage A of operation, to be described, as for example before knitting has commenced; and for convenience the left side of this figure will be considered the front side of the machine, being the side toward which the knitting progresses and is more readily observed.

Fig. 2 is a top plan view of a portion of the machine shown in Fig. 1, with the parts however in the later stage or position D cut with the fabric omitted; the machine may have many knitting units or sections, Fig. 2 showing the extreme right hand unit, and a small portion of the next adjacent unit, both being broken away for convenience of the figure.

Fig. 3 is a section view taken on the section line 3—3 of Fig. 2 or Fig. 4 looking from the front, but extending only part of the length of the section line on Fig. 2. Fig. 4 is a section view taken on the section line 4—4 of Fig. 3, looking from the right. Figs. 3 and 4 are on a larger scale than Figs. 1 and 2, and they show the same stage or position A of the parts as in Fig. 1.

Fig. 5 is a section view taken on the line 5—5 of Fig. 2, looking from the right, and on the same scale therewith, showing details of the fabric takeup.

Fig. 6 is a top plan view of the welt bar and its adjacent mountings, in the same position D as in Fig. 2. Fig. 7 is a section view taken on the line 7—7 of Fig. 6, looking from the right, the parts being in the same stage or position D, but certain parts being shown also in broken lines in position M to be described. Fig. 8 is a section view taken on the line 8—8 of Fig. 6 or Fig. 7, looking from the front, with the parts in the same position. Figs. 6, 7 and 8 are all on the same scale, larger than that of Fig. 2.

Figs. 9 to 17 inclusive constitute a series of diagrams in left elevation showing the preferred movements of the principal knitting instruments in their operations according to the present invention, some of these diagrams showing several successive positions or stages of action, so that in all sixteen positions or steps are illustrated, marked as positions A to P inclusive; Figure 15^a being an enlargement of the middle portion of Fig. 15, and Fig. 17^a a similar enlargement of Fig. 17, to show more clearly these congested parts; while Fig. 16^a is a front elevation view showing how each needle and hook, although operating in the same plane, can relatively pass each other.

Fig. 18 is a detached view of a portion of the bearded needle illustratively used with the present invention; and Fig. 19 is a similar view of a portion of the illustrated welt hook; these being more or less conventional, and it being understood that other forms of needle or welt hook can be used. Fig. 20 shows a modified construction of welt hook and welt bar having special advantages.

Figure 21 is an enlarged sectional view showing the combination and association of elements constituting the welt forming and turning mechanism and particularly illustrating the cooperative relation of the welt bar carriage assembly and the automatic means for controlling the lifting and lowering movements thereof to preposition the welt hooks in relation to the needles. Figure 22 is a detail showing in elevation of the parts cooperating to effect the tilting swinging movements of the welt bar.

Before describing the details of the mechanism shown on Figs. 1 to 8 the diagrams Figs. 9 to 17 and subsequent figures will be referred to, first by describing the principal instruments cooperating in the knitting and welt forming, which mostly are shown also on Figs. 1 to 8. The yarn laying carrier and various other groups of parts are wholly omitted as being well understood.

The needles 20 are shown of the spring beard type, with the beards 21 at the rear. In the usual knitting machines the needles stand substantially upright, and will be so considered for description purposes. The beard is at the top end, the extremity of which is considered the apex of the needle. As usual the needle may have a groove 22 in its shank, Fig. 18, to receive the tip of the beard when pressed into it at certain times.

At their lower ends the needle butts 23 assist the clamping of the needles in the usual needle bar or bed 24 (Figure 1). The bar and needles go through various conventional movements, upward and downward, frontward and backward. These may be of one kind during knitting effected by a usual actuating and control or cam mechanism. The needles and cooperating sinkers and knockovers may have a second kind of actuation, with movements known as narrowing motions, caused by a different set of cams, as usual. This special narrowing motion may be much slower than the regular knitting motion, for example with one cycle or main cam shaft rotation in about five seconds, as against about one second for regular knitting. This narrowing cycle or motion of needles, sinkers and knockovers may be utilized for the welt forming operations indicated by the diagrams, Figs. 9 to 17.

The sinkers 26 may be conventional, each with its yarn-engaging throat or notch and a front extension or nose. As usual, the sinkers are separately slideable frontwardly during the laying of the yarn in each course, being pushed frontward in succession by a traveling cam or slurcock (not shown) acting through jacks which thrust upon the rear ends of the sinker shanks 27. The bank of sinkers may consist of regular sinkers alternated with special sinkers or dividers, all as conventionally understood.

The sinkers may be mounted slidably in the usual head or multiple slideway 28. This sinker head or block may be in fixed position in the machine, and a front portion of it, adjacent to the sinker noses, may be extended sufficiently frontwardly to constitute a beard presser 29 or press-edge, taking part in the knitting and transfer operations at certain stages of the movements of the movable instruments.

Cooperating with the bank of united needles and bank of separate sinkers is a corresponding bank of united knockovers or bits 31, these being notched members, usually mounted on a bar 32 by which they are put through certain frontward and rearward and perhaps other movements at a level just below the series of sinkers.

During welt forming these described loop-forming instruments 20, 26, 29 and 31, cooperate with the series or bank of united welt hooks 33, the latter receiving the first formed loops, retaining and retracting them frontwardly during the knitting of the welt, and then restoring such course back to the knitting needles.

Each welt hook may be of conventional construction as separately shown in Fig. 19 or may be modified in various ways, for example as in Fig. 20. This welt instrument has a hook end 34, and its shank has a groove 35 engageable by the needle beard during transfer, and beyond such groove it has a shoulder or hump 36 constituting a stop or limit to the slipping of a loop along the shank, and at the far end a butt 37. The welt hooks are clamped by their shanks and butts in a welt bar 38, from which they project in parallelism.

The welt bar 38 is fitted to be movable in various ways by means of mountings to be described, and with the bar and mountings are combined mechanism and connections for causing such movements, namely upwardly and downwardly, rearwardly and frontwardly, tiltingly to change the posture of the welt hook, and also transversely of the direction of knitting, for slight offset shifting to bring the several welt hooks either into

the fore-and-aft planes of the corresponding needles or equi-distantly spaced between them.

The welt hook 33 has three bends near its center to produce the hump or loop stop 36. In the modified hook 33a of Fig. 20 one bend is omitted, simplifying the hook, and so disposing it relatively to the welt bar that when the hook is tilted over to the extreme rear, as at stage M, Fig. 17, a safer clearance is afforded between the welt bar and the sinker head or other parts to the rear.

Another instrument taking part in the welt operation is the so-called welt rod 39 adapted to be engaged upon the fabric web after the knitting has started and to assist manipulation of the fabric by exerting a frontward pull thereon as the fabric lengthens with the progress of the knitting.

In further explanation of the diagrams, which show only one of each of instruments 20, 26, 31 and 33, certain arrows indicating the general direction, but not distance, of movement have been applied in certain figures to the movable elements, the needle, the sinker, the knockover, the welt hook, the welt rod. These arrows indicate approximately the movements which the elements have just undergone to reach the position shown in each figure; for example, the needle has moved downward, the sinker rearward, and the welt hook rearward, in coming to the Fig. 9 position. Further, the initial thread course or series of loops is designated *x*, while the fabric knitted to constitute the welt is designated *y*, and the final loop course of the welt, with which the initial course is to be combined, is designated *z*. The various positions or stages shown in sequence are designated respectively as initial position A, shown in Fig. 17, position B in Fig. 9, C and D in Figs. 10 and 11, and E to P in Figs. 10 to 17, sometimes several positions in a single figure, the series of movements terminating with initial position A following the last mentioned position P; thus completing the cycle of the preferred welt forming movements of this invention.

The welt forming operations may be described on the disclosure of the diagrams as follows. Initially the welt bar and hooks stand retracted fully frontward as in position A, Fig. 17, the needles being elevated, the sinkers rearward and the knockovers in the position shown in Fig. 9. The thread carrier then lays at least one course of yarn along behind the bank of needles upon the regular sinkers, which push frontward successively, creating yarn loops, which are then divided in the usual way, all the sinkers eventually returning to the Fig. 9 position. The needles then descend to the Fig. 9 position, and the first course of loops rests on the sinkers, the loops engaged in the needle beards. With the described laying of the first course the knitting action will have been stopped, or at least slowed down to suspend the knitting motions until the welt hooks have received the first loops and retracted. For this hooking-up operation the welt bar and hooks move rearwardly, during which motion they are side-stepped slightly, to the extent of a half loop or needle space, so that the welt hooks may pass between the needles. With this we come to the position shown in Fig. 9, referred to as position B of the active elements.

Position C is shown in Fig. 10, the needle bank having swung frontwardly and descended, thus carrying the initial loops from off the sinkers, the welt hooks receiving them, between the

needles; the knockovers also supporting the loop course.

Position D, Fig. 11, shows a considerably later stage, after an extended length of welt fabric has been knitted. The welt hooks have retracted frontwardly with the progress of the knitting. At a proper stage the welt rod 39 has been laid upon the fabric and tensioned by the usual straps to give frontward pull thereon. For convenience the sinkers are shown moved substantially frontward between the needles and the needles in their elevated position, with new course of loops *z* thereon. Thus position D is arrived at.

Having knitted the desired length of fabric the knitting must next be suspended for the transfer operations. No yarn is to be laid, but the needles, sinkers and knockovers are to cooperate in the transfer by the welt transfer motion, which as explained may be identical with the narrowing movements of these instruments, enabling the same cams and connections to be used as in narrowing, the main cam shaft turning at the slow rate of five seconds, sufficient for the transfer.

Fig. 12 shows position E, through which the hooks pass, following position D. Following position E Fig. 12 shows also positions F, G and H. In position E the welt hooks have started to shift rearwardly, so that the initial loop course *x* has slid along the hook shank to the shoulder 36. With the continued rearward movement the welt bar and hooks are simultaneously bodily elevated, and are tilted down at their free rear ends, and are then lowered while the tilting continues, as shown by the successive positions F, G and H. Thus the hooks are caused to vault over the needles and descend until the hooks now stand in substantially upright position behind the needles. In the meanwhile the needles have descended, while the sinkers and knockovers have retracted rearwardly, the latter cooperating in sustaining the fabric. These transfer movements have occurred with each hook moving in the plane of its needle, at least as to position H, such alinement being assisted by the confinement of both needles and hooks between the knockovers, and later between the sinkers.

The tilting of the welt hooks and bar from positions E to H is assisted by the pull of the fabric thereon, as will be clear from Fig. 12.

Fig. 13 shows position I, wherein the sinkers have advanced, now above the fabric and loops. The needles have shifted rearwardly, and this has brought their beards into engagement in the grooves of the respective welt hooks. This is a positive action, coupling the needle to the hook, and the needle swing is continued until the welt hooks, yieldingly mounted, have even been tilted substantially by the pressure of the needles, the welt bar being mounted for such yielding tilt as will be described. The needle and hook have thus become coupled in a reliable manner for the transfer of the initial loops *x* from the hooks to the needles which already carry the final loops *z*.

Fig. 14 shows position J, wherein both the welt hooks and needles have risen, but the needles further than the hooks. The needles have thus been caused to slide up on the hooks and enter the initial loops held by the welt hooks. During this action the welt hook shoulders hold down the loops as the needles relatively rise. When the hooked type of knockovers is used the hooks thereof act to hold down the loops, as shown; otherwise the sinkers may assist in this action, in

which case the needles and welt hooks should be lifted somewhat higher.

Figs. 15 and 15^a show position K, wherein the needles and knockovers have now shifted forwardly, permitting the welt hooks to swing back from their tilted to their vertical position H, and the hooks having been extensively elevated and caused or allowed further to tilt rearwardly by way of commencing their movements of extraction from the transferred loops x. Fig. 15^a shows the critical part of this position on an enlarged scale, with each of the initial loops extended between the welt hook and the notch or hook of the knocker. Preferably an upward tension is maintained on the welt hooks at this stage, by a resilient lift of the welt bar. The needle beards now occupy the loops, and the tips of the welt hooks stand down slightly below the apexes of the needles, at which level they are to return forwardly without need of rising above the needles.

Fig. 16 shows position L wherein the needles have been swung slightly rearwardly again, commencing an overlapping movement between the needles and welt hooks, as the hooks come relatively forward in the process of their disengagement. Although the two instruments are working in the same fore-and-aft vertical plane this passing movement is feasible on account of the very thin and narrowly tapered character of the extremities of the needle and hook respectively. There will be a slight contact between the two, this motion being illustrated in the enlarged front view Fig. 16^a. It is not necessary, but in fact would be undesirable, to attempt a bodily side shifting movement of the welt bar for this purpose, since it would tend unduly to distract the loops. The passing movements of the two then, according to the described operation, involves a slight contact near the extreme tips of the two instruments, and since these are tapered thinly and have no surfaces that can catch, they readily pass each other with only a very negligible extent of deflection or bending of one or both thereof. It is found that it is safe to leave entirely to chance the relative passing of the hook and needle ends in the motions of disengaging the hooks from the loops, and each of the hooks may pass either to the right or left side of its needle, as chance dictates.

Fig. 17 shows the succeeding positions M, N, O and P, and finally the initial position A of the welt hooks, with all of the parts restored, so that continued knitting may be resumed. In position M the welt hooks have been tilted further back than in position L, in a manner not merely to throw the hook ends further forward, but to swing the barb end of the hook to horizontal so that it can slide out of the loop by simple forward shift. The enlarged view Fig. 17^a makes this clear. These movements operate to extract the hooks from the loops, leaving the loops surrounding the needle beards, at a level between the sinkers and knockovers, and still engaging the hooks of the knockovers. In positions N, O, P and A the welt hooks are merely first shifted further forward and then tilted back to an upright position and swung over around forward until resuming fully retracted initial or horizontal front position A. The welt having thus been completely formed and transferred, and the welt bar retracted, the regular knitting motion may be resumed, and the initial and final loop courses x and z of the fabric welt y become combined and locked into the next succeeding loop course.

It remains to describe the fittings and actuating

mechanism and connections for bringing about the described operations. As to the needles 20, sinkers 26 and knockovers 31, these all have well known automatic motions and cooperation during regular knitting, afforded by regular knitting cams, for which however are substituted a different set of cams to give the different motions and cooperation used during the welt forming, as fully indicated by the diagrams. As already explained the well known narrowing motions may be substituted and serve for the welt operations. To avoid undue illustration and description the means for causing such regular motions and the special actuation of these instruments for narrowing or welt forming are wholly omitted herefrom; it being understood that as usual the special movements are afforded by a temporary interchange from the faster regular or knitting cams or pattern control to the special or narrowing cams or pattern control, of slower speed, which latter may be readily designed and constructed by a skilled worker in the art from the disclosure herein afforded of the relative movements and timing of these instruments.

Reciting next the preferred movements of the welt hooks hereof, these are performed by the mechanical manipulation of the welt bar; and the hereinafter following description will disclose fully the fittings or mountings of the welt bar, permitting the necessary movements, and the preferred actuating mechanism and connections to bring about these movements in the disclosed sequence, preferably by automatic timing. To assist a clear comprehension, the welt bar movements will here first be recited and analyzed.

One welt bar movement is the slight side shifting of the bar, at the hooking-up stage to bring the hooks into positions halfway between the vertical fore-and-aft planes of the needles, and at the later or transfer stage their restoration into the needle planes. This side-stepping into mid-space positions need prevail only during and near positions B and C, wherein the hooks enter their loop-receiving position between the needles. The other hook movements may all be and preferably are performed with the hooks in the same planes with the needles. These subsequent movements, illustrated particularly by Figs. 12 to 17, may all be performed by three components of movement, first, the rearward bodily advance of the welt bar and its complementary forward retraction, and second the bodily rising and lowering thereof, and thirdly, the bodily tilting of the welt bar and hooks, which may be described as an oscillating movement, by which the posture of the hooks is changed from one extreme at position E to the opposite extreme at position M and thence back to initial posture at position A. These combined motions resemble during advance a vaulting of the welt hooks over the needle line as a hurdle, with a different return movement.

Coming next to the general elements of the machine as shown in Figs. 1, 2 and others, the heavy fixed frame extends the full length of the machine. It comprises a series of upright cross walls 45 which serve also as bearings for various shafts that are longitudinal to the length of the machine. Among the fixed lengthwise frame members are the so-called table 46 in the upper central part of the machine, and various other structural or angle members 47, as well as rods 48 which frequently constitute axles. At the upper rear are brackets 49 for supporting the mountings for a series of carrier rods 50 from which may depend the usual yarn carriers, not shown.

A series of high fore-and-aft brackets 51 support certain parts to be described.

The main cam shaft 53 is at the lower central part of the machine, this carrying a number of cams, as usual, including a cam 54 taking part in the lifting and lowering of the welt bar, and a cam 55 taking part in the rearward and forward shifting thereof, as will be further referred to. The cam shaft may have controlled drive means for rotating it at a faster speed for the knitting motions, as usual, and a slower speed for the narrowing and welt forming motions as explained. It may be shiftable lengthwise to put into action one or the other set of cams, for the respective motions. The usual hand wheel 57 is on a shaft 58 on brackets near the front of the frame walls 45, and thereabove is located the control rod or shaft 59 on an extension bracket 60.

The welt bar 38, Figs. 1, 2, 6 and 7, consists primarily of the usual complementary side parts between which the welt hooks are clamped in parallelism by their shanks and butts. By the connecting screws 65 the welt bar parts are rigidly united. At each end beyond the series of hooks the bar has attached to it by screws 64 a somewhat enlarged head 66, these heads having a rounded oblong shape, as Fig. 7 shows, and constituting the means by which the welt bar is mounted and manipulated. The tilting or swinging movements of the bar take place about two pivot studs 68 by which the bar heads are mounted on the cradle parts 74 of two carriages 75 to be described. This mounting is provided by extension ears 67 one on each head, in each of which is secured one of the pivot studs 68, and the two studs being in axial alignment, parallel to the length of the welt bar, as best shown in Fig. 6.

The several movements of the welt bar may here be further explained. Its tilting or oscillating movements take place about the axis represented by the studs 68. These studs have their bearings in upstanding ears 80 formed with the cradle parts 74 of the welt bar carriages 75, one at each side. These carriages are shiftable rearwardly and forwardly to provide that component to the welt bar. The carriages in turn are mounted on what may be broadly termed an elevator, shown in the form of a rockframe or rocker members 100, fulcrumed considerably to the front, and capable of rising and lowering movements, to afford that component to the welt bar operations. The slight side-stepping movements of the welt bar for a half needle space are preferably brought about by a self-acting device taking advantage of the cam-actuated movements of the carriages or rockframe. Also, since the tilting movements of the welt bar may accompany the rearward and forward movements thereof the tilting movements are preferably also effected by a self-acting device operated by reason of the other movements, in a manner to cause rearward advance and a different forward return, as shown on the diagrams. Thus all the welt bar movements may be automatically performed from but two active cams, for example cams 54 and 55 on shaft 53.

By way of completing the description of the welt bar 38 reference is made of the tapered extension piece or cam finger 69 at each side, attached rigidly to the bar head 66, for example being fast on the stud 68. These cam fingers 69 as more clearly shown in Fig. 7 extend from the axis of swinging in a direction opposite to the welt bar itself and in the same direction as the welt hooks. Thus in Fig. 7 the welt bar rests

initially in the carriage cradles 74, its width extending frontwardly from its axis represented by the pivot studs 68, while the cam fingers 69 and the hooks extend rearwardly from the axis. In this figure the dotted lines show the welt bar and hooks tilted over to their extreme rear position M, in which position the cam fingers depend from the axial stud. The fingers 69 during the rearward movement are adapted to contact the sinker head 28, at its press edge 29, thus camming down the finger and assuring the proper starting of the welt bar tilting action, in case the other tilting means fails, which is to be described.

The welt bar pivot stud 68 at each side is mounted on the rear end of a rearward extension or cradle 74 of the aforesaid sliding member or welt bar carriage 75, at that side. The two carriages are arranged to act together, as though united, although necessarily spaced well apart, as Figs. 2 and 6 show, for the accommodation and operation of other mechanism between them. The two carriages are slideable rearwardly and frontwardly, that is, to the right and left in Figs. 6 and 7, upon the symmetrically opposite pair of rocker members 100, which are fulcrumed at their front ends on an axle 105, as shown in Figs. 1 to 4, said members acting in unison as an elevator to raise and lower the connected carriages and welt bar. The two rocker members, swinging up and down as though united, may be considered as a rockframe. While the rocker members may be rigidly interconnected they are more conveniently unconnected but are lifted and lowered in unison by means actuated from the main shaft 35 cam 54, as later described.

Each of the carriages 75 slides longitudinally upon its elevating rocker member as a guide, and the construction may be substantially as follows. The flat body of each carriage overlies the rocker 40 member, and it is mounted upon a slide or shoe 76 running in a groove or way cut into the top portion of said member. To this shoe is connected by screws 77 a stiffly flexible band or steel strip 77, by which the sliding movements of the carriage are effected from front connections to be described. A slight resilient uptilting of the front end of the carriage is desirable, for yield at certain times. For this the underside of the carriage is grooved to accommodate an elevated portion 76^a of the shoe 76, best seen in Fig. 8; while the rear end of the carriage is pivoted by a horizontal pin 75^a, see also Figs. 6 and 7, to the shoe. A headed post 78 stands up from the shoe through a slot in the carriage, while a stiff spring 79, compressed between the post head and carriage holds the latter yieldingly down upon the shoe, for all normal operations.

When the two carriages 75 are shifted in unison, sliding along the parallel rock members 100, and carrying with them the welt bar, a sort of telescoping action takes place, the rockframe being effectively lengthened with the rearward shifting of the welt bar and vice versa. Instead of mounting the welt bar ends or heads 66 directly upon the carriages they preferably are mounted upon the aforesaid cradles 74 which are part of the carriages and extend rearwardly therefrom. Each cradle has an upstanding ear 80, and these ears constitute the fulcrums for the welt bar pivot studs 68. The cradles are shaped for the welt bar heads to rest normally thereon in initial welt bar position, as best shown in Fig. 7.

The cradles in turn are connected, each to its carriage, so as to be capable of relative rearward

movement, preferably resiliently, against the pull of a restoring spring. Thus, each cradle is mounted at the rear end of a slide rod or stem 81, which passes through a guide on the carriage in the form of two bearing lugs 82, standing inwardly from the carriage body. Each cradle itself constitutes an enlarged head to its stem, and comes normally to a stop against the rear lug 82 as shown, where it is yieldingly held by a longitudinal restoring spring 83, extending between upstanding posts 84 on the cradle and 85 on the carriage.

When the two carriages 75 are moved rearwardly in unison, as between positions D and H, and return, they carry with them the two cradles and pivoted welt bar. When however the carriages are being pulled forward with the growth of the welt fabric, after position C, the yield of springs 83 may function to smooth the action. The knitting motions cause jerking and wiggling at the needles, requiring cushioning of the forward pull upon the fabric. The springs 83 become stretched as they yield for this pull, to be described, and introduce the necessary yield, during the first part of the knitting of the welt, which yield later on is provided by other means.

In respect to its tilting motions also the welt bar is preferably held resiliently in its normal relation to the cradles and carriages, and is resiliently tilted, for example by the following means. As shown in Figs. 6 and 7 there extends, from each welt bar head a link 87, pulling forwardly thereon, leftwardly in these figures; and the front end of the link is pivoted to the upper arm of a rocklever 88 which is centrally fulcrumed on the cradle 74, its lower arm carrying a stud or roller 89, normally pressed yieldingly rearwardly. This resilient pressing is accomplished by means of a push bar 90, having a depending rear lug or contact 91 and a front contact lug 92. The rear contact 91 normally bears rearwardly against the stud 89. The bar 90 is slideable in a groove in the under side of the carriage, and is pulled rearwardly by a spring 93 extending in tension from a post 93^a on the bar to a post 93^b on the carriage. When the welt bar is tilted over rearwardly by other means the spring 93 yields and becomes tensioned, and it later exerts its pull to restore the parts by reversely tilting the welt bar back to normal, as the carriages return forwardly, the front contact lug 92 then contacting the front side of the front carriage lug 82, as shown in Figs. 6 and 7.

Each push bar 90 is preferably positively limited in rearward movement when the carriage advances fully to the rear, the latter being shown in an intermediate position in Figs. 2, 6 and 7. For this purpose a stop flange or contact 94 is shown, standing outwardly from a slotted plate 94^a screw-attached to the rocker member 100 at each side, Figs. 7 and 8. When the front contact lug 92 of push bar 90 meets contact 94 the bar ceases rearward shift with the carriage, while the spring 93 becomes distended with further carriage shift.

The tilting movements of the welt bar from initial position may be effected by action upon the same two studs 89 located at the lower ends of the opposite rocklevers 88. Thus an upstanding contact piece or shoulder 95 is shown located in the rearward path of the stud and mounted at the rear end of an extension slide or shank 96 offset from the front shank portion 96^a mounted upon each elevating rocker member 100. Each shank portion 96^a is shown slideable

against the body of the rocker member 100 beneath the angle piece or cover thereof, and is confined by a rear clip 97 and a front clip 97^a, the latter constituting an eventual stop for the 5 forward return of front contact lug 92, bar 90 and carriage 75, as Fig. 4 shows. A spring 98 extending between front clip 97^a and the shank portion 96^a pulls forwardly on the shank, permitting rearward yield, while the rear clip 97 forms a limiting stop, contacted by the shank bend 95^a (Figure 6), in opposition to the spring.

The contact piece or shoulder 95 stands up in the path of the stud 89 when the carriages and welt bar are shifted rearwardly, so that, as shown 15 in dotted line in Fig. 7, the stud strikes the contact piece or shoulder when reaching a certain point in its movement, at about the same time the stop flange or contact 94 stops the rearward advance of the rear lug 91. With the continued 20 rearward shifting movement the contact piece or shoulder 95 rocks the rocklever 88, by pulling relatively forward on it, this acting through the link 87 to swing upwardly and over, to the dotted line position, the welt bar and connected parts. The yield of spring 98 cushions this tilting action, and provides a necessary later yield in the welt bar operations, when other actions cause tilting thereof. The operation of the welt 25 bar tilting connections will be described further below, including the safety action of the cam finger 69 which can give a positive start to the tilting, preferably just in advance of the action of the contact piece or shoulder 95.

Referring next to the rocker members 100, 35 preferably parallel, slidably supporting the carriages 75 and together constituting in effect a rockframe which may swing up and down during manipulations of the welt bar, these rocker members are shown fulcrumed at their front ends, and 40 having means operating at their rear ends to elevate and lower them in unison. As best shown in Figs. 4, 6, and 8 the body of each rocker member is a channel, with top groove in which the carriage shoe 76 slides, while the steel strip 45 77 attached to the shoe overlies the two sides of the channel; and is there confined, with sliding fit, by angle pieces 99 overlying the strips, depending at the sides and rigidly attached by screws. Each rocker member at its front end 50 merges into the rim 101 of a circular housing or wheel which has a web 102 extending inwardly to a hub 103 that surrounds and turns loosely on a bushing on a shaft 105 serving as an axle. See also Fig. 3. Thus the two rocker members 55 are fulcrumed at the front with the shaft 105 as a center.

For lifting the rear ends of the two rocker members each is provided with an outwardly projecting roller stud 107, see also Figs. 1 and 60 7. These studs preferably are mounted not directly on the rocker member, but on slides or plates 106 adjustably secured to said members, for the accurate positioning of the studs. The 65 studs constitute the contacts or cam followers for the lifting action; and below them are oscillating cams 108. The two cams are mounted on a common shaft 109 located near the rear and extending the full length of the machine, and 70 having such a pair of cams at each knitting section. By suitably rocking the shaft 109 the cams will swing upwardly, moving the two rocker members in unison, thus elevating the welt bar, and later lowering it, to accord with the described sequence of operations.

When lowered the rocker members may rest upon the cams, or some fixed member, for their initial position. For example, a fixed but adjustable rest 110 is shown in Fig. 7 for each member 100. To ensure the prompt descent of the rockframe each member is shown pulled downward towards its rest 110 by a spring 110a.

The lifting of the rockframe and welt bar may be performed by rocking the shaft 109, which, for example, carries a rockarm 111 to the right of the end frame 45, connected by a drop link 112 with a cam lever 113, Figs. 1 and 2. The lever 113 has a front fulcrum axle 114 and carries a follower 115 adapted to be positioned upon the cam 54 of the main shaft 53 for the welt forming operations. In a usual manner the hub of the follower 115 may slide on a stud 116 on lever 113 into and out of operating position, and this shift may be performed by a shift lever 117 pivoted on the lever 113, with its free front end engaged by a spring and collar shift means on a shift rod 118 controlled from a suitable timing means or pattern chain during the knitting of a stocking. Thus the cam 54 and follower 115 may be rendered active for the period of the welt transfer operations and then inactive for the completion of the stocking.

The two rocker members 100, lifting and lowering in exact unison, may be considered a rockframe or weltframe, since they may just as well be rigidly interconnected into a unitary frame or carrier, liftable and lowerable to lift and lower the two carriages 75 carried on it, without any difference in action or result. Such rockframe or weltframe constitutes the elevator for lifting and lowering the carriages and weltbar, while permitting the rearward and forward carriage movements, performed by the actuating connections or flexible steel strips 77, and the tilting weltbar movements, performed by self-acting connections.

The welt rod 39 by which forward tension is placed upon the lengthening fabric may be operated for this purpose in the usual manner of take-up devices, the details indicated in Figs. 1, 2 and 5. The rod ends are laid or engaged in open hooks 38a each mounted on a fabric-take-up strap 40, which, at the rear passes around the shaft 109 upon a supporting plate 40a mounted on the fixed table 46. The two front ends of each strap 40 are attached respectively to upper front and lower rear spools 41 and 41a mounted respectively on upper front and lower rear shafts 42 and 42a. By this arrangement as one spool takes up, the other lets out, the strap. To compel the spools to turn in unison their shafts are interconnected by spur gears 43. To afford a yield in each strap and keep it taut, a stretchable device 40b is included at a looped part of its length. In order to give a constant resilient pull forwardly to tension the fabric the shaft 42 is shown as extended rightwardly to a convenient point at which it is provided with a pulley or drum 44, around which is wound a take-up cable 44a, maintained under constant pulling tension, for example by passing over an overhead pulley, not shown, and thence down to a counterweight. A handle and ratchet device 44b is shown for turning the shaft and operating the take-up rod manually, or anchoring it at any desired rearward position.

Describing next the mechanism for shifting rearwardly and forwardly the two steel strips 77 and the welt bar carriages to which they are 75

attached, each of these strips is shown as mounted on the rim 120 of a wheel. The webs 121 of the two wheels have hubs 122 both mounted fast upon a sleeve 123 which can turn loosely on the shaft 105, see Figs. 2, 3 and 4. Normally these parts are coupled to turn with the shaft 105, which therefore can move the two carriages in unison. As a means of so clutching each of the two strip actuating wheel rims 120 to the shaft 105 there is shown a hub 125 fast on the shaft, at each side, from which extends outwardly a clutch disk 126 located between the webs 122 and 121 already described. Each of the disks 126 has a clutch recess 127, and cooperating with this is a spring dog or plunger 128 mounted on the web 121, the spring tending to thrust the dog into the recess for clutching purposes. The stem of the spring plunger has an external button 130 which is flanged, the flange having notches 131 cooperable with a small projecting tooth or positioning screw head 132. By this arrangement, when the notches are occupied by the screw heads 132 the clutch elements are engaged, whereas by pulling outwardly on each button and turning it slightly the plunger may be held inoperative by the screw head, and the wheel and strip thus unclutched from the shaft 105. This uncoupling is merely to release the steel strips 77 and carriages 75 for manual operation, adjustments etc.; and normally the clutches are closed so that the wheel rims 120 are in effect fast on the shaft 105, whereby the turning of the shaft shifts the two carriages in unison.

The entire set of parts in each knitting section 35 on shaft 105 is confined on the shaft against endwise movement by means of left and right collars 133, between which are the two hubs 103, the two hubs 125 and the long sleeve 123. The shaft turns in the series of brackets 51, as do also the shafts 42a, the brackets being mounted upon the frame table 46. A slight clearance or gap 134 is shown, between one of the collars 133 and a bracket 51, thus affording slight endwise play of the shaft and parts to an extent approximately, or slightly less than, a needle space, for a purpose to be described.

As explained, during welt forming operations, the turning of the shaft 105 in one direction or the other will effect the simultaneous shifting of both carriages in every section of the knitting machine, in forward and rearward longitudinal directions. A restoring arrangement is provided giving a tendency to retract forwardly the two carriages, and this is shown in the form of a pulley 135 on the right end of the shaft 105, Figs. 1 and 2, a cable 136 being wound around said pulley and being tensioned by a counterweight, similarly to the cable 44a, so that the pull of the cable turns the pulley and shaft counterclockwise in Figs. 1 and 4, rotating the shaft to pull forwardly the carriages. This pull occurs during the first part of the knitting of the welt, following position C, tensioning the fabric. It is strong enough to stretch somewhat the springs 83 between carriages 75 and cradles 74, so that these springs cushion and smooth the fabric pulling action.

The operative movements of the two carriages however, during hooking-up and transfer, are performed by accurate cam timing, and for this purpose the following connections are shown. Mounted on the shaft 105 is a spur gear 140, Figs. 1 and 2, and this is in constant mesh with an underneath sliding rack 141. Thus, by shifting the rack rearwardly or forwardly the desired car-

riage and welt bar movements are effected simultaneously in all sections of the machine. A way 142 is provided for the guidance of the rack, which may rest upon a fixed plate 143. The rack movements are effected through a link 144 extending between the rack and the upper arm 145 of a bell crank lever fulcrumed at 146, its rear arm 147 being loosely connected by a slotted drop link 148 with a cam lever 149 fulcrumed on the axle 114. The slot allows the lever to drop relatively, when idle, or when the shaft 105 is under control of the cable 136 and the growing fabric. The cam lever 149 carries a follower wheel 150 which is slideable upon a stud 151 so that it can be placed in operative relation with the cam 55 on the main cam shaft 53 below, or shifted to inoperative position as shown in Fig. 2. To effect such shifting there is shown a shift lever 152 fulcrumed on a stud projecting from the cam lever 149, the front end of the shift lever engaging and being controlled in its movements by the shift rod 118 heretofore mentioned.

For causing the accurate slight side-stepping movements of the welt bar, for example rightward one half needle space for the loop taking operations, positions B and C, and leftward to bring the hooks into the needle planes for positions E to P, or at least H to N, the following plan is preferred. As already explained the shaft 105 has a slight play lengthwise of the machine, represented by the gap 134 adjacent a collar 133, and being preferably equal to or possibly slightly greater than the required extent of welt bar side-shift. The approximate shift by taking up the gap 134 is not of sufficient accuracy to be relied on for the shift of the welt bar between its two positions, and herein is shown a finer adjustment to exact position, applied independently for each knitting section, ensuring perfect operations in each.

The plan hereof is to use, in each knitting section, a cam device, preferably between a fixed part and the carriages or welt bar, which effects the necessary side shift with assurance of accuracy. As shown this takes the form of complementary cams or cam faces, thrusting rightward on the rocker members 100 or carriages 75 for one adjustment and leftward for the other, thus causing each welt bar to take its respective positions, with the hooks between and in the planes of the needles respectively. Passive or self-acting cams are preferred, operating by reason of other movements of the rocker members or carriages, and located at the rear, approximately in line with the welt bar. The thrust may take place by utilizing the gap 134, the shaft 105 and rockframe etc. merely sliding along the length of shaft 105 to the extent of the gap, and the self-acting or cam device then acting to cause the final exact adjustment. The provision of loose play in the mountings, preferably the sliding of shaft 105, avoids any need of bending or straining the intermediate parts for the side-stepping adjustment in each section.

For these purposes the lefthand carriage 75 in each section carries a leftward facing cam or plate 160, shown screwed to the left or outer side of the carriage; and the righthand carriage has an oppositely arranged similar cam plate 161. See Figs. 6-8. These plates for convenience are shown square, and each has a general or low area and a minor area or patch in the form of a wedge or cam surface 162 or 163, in a slightly offset or raised plane. The two cam plates cooperate, being

complementary; and thus the two cam surfaces 162 and 163 are differently located on their respective plates, each cooperating with the general or low area of the other member.

5 Cooperating with the left carriage cam plate 160 is a fixed-position contact member, or cam follower, in the form of a roller 164, on a frame bracket 165, and so positioned that the roller may act on the cam surface 162 of plate 160 as 10 the carriage moves rearward at a low level, during hooking-up, as in Figs. 6 to 8, thus to thrust the carriage and welt bar rightward. The parts still stand leftward as the cam plate has not yet reached the roller 164. Similarly at the right is 15 a contact roller 166 on a fixed bracket 167, so that when later the carriages move rearwardly at a high level, during transfer, the roller acts on the cam surface 163 of the right hand cam plate 161 to thrust leftward the carriage and 20 welt bar. In each case when either cam surface 162 or 163 is active on its roller, the roller at the other side runs on the general area of its cam plate. As the cam plates may be very accurately machined, and the rollers exactly located, the 25 positioning of the welt bar is exactly performed, and in each operation its position is positively determined, independently in each knitting section.

At positions B and C the rockframe, carriages 30 and welt bar are at a low level. The right cam surface 163 is inoperative, as in Figs. 6 to 8, but the left cam surface 162 meets the roller 164 before the hooks reach the needles, thus offsetting the hooks to enter safely midway between the needles. A preferred plan is that the shaft 105 and connected parts and welt bar normally stand at the leftward adjustment, as 35 shown in Figs. 2 and 3, with the gap 134 at the right; but this is not necessary, since if the parts should be at a midway position, the cam surface 162 will merely deliver a shift of only one quarter of a needle space. Later, for positions H to N, when the rock frame has been lifted, the cam surface 162 becomes inoperative because higher 40 than its roller 164, but the cam surface 163 comes into level with its roller 166, so that at this part of the operations the welt bar is adjusted leftward, to the correct extent, for the hooks to move wholly in the planes of the respective needles.

The two cam plates 160 and 161, while both 45 open cams, face oppositely, namely from each other, and towards their rollers, and they are therefore in effect a closed cam; and manifestly 50 one of the two could be dispensed with, if some equivalent means be employed to hold, for example the cam surface 162 of the plate 160, in contact with its roller 164, such as a spring, or other resilience, operating to take up slack by 55 leftward thrust. Greater reliability however is afforded, and a more open and accessible structure, by the disclosed arrangement, the left cam plate causing rightward thrust for the mid-space 60 positioning of the welt bar and hooks, and the right cam plate the leftward thrust for positioning them in the needle planes. Each knitting section has its separate individual adjusting means, while the slight endwise slip of shaft 105 and carried parts operates the same for all of the 65 sections. No special actuation is necessary for such shaft movement, since the cam plates of all the sections afford a combined thrusting force, first rightward and later leftward, for this 70 purpose.

75 A convenient auxiliary attachment for han-

dling the welt rods 39 of all knitting sections is shown in Figs. 1, 2 and 5 operable about the time, between positions C and D, when the welt bar 38 has retracted with fabric to the full extent of its forward movement, corresponding to the initial forward carriage position of position A, as shown in Figs. 1 and 4. To save the separate manual placing of a welt rod in each of the multiple knitting sections the following means is shown. Each section has a spring clip or rod-holder 170 at each end of the rod 39 in an idle position, shown in Fig. 1. Each clip is on a carrying arm 171, normally resting in forward swing position. Each arm is swingable over and back to operative position, partly shown in Fig. 5, being attached to a rock shaft 172 for this purpose. The same rockshaft carries all the arms 171, throughout the length of the knitting machine, and may be operated, as manually, from any point in its length, for example, by a handle or wheel, not shown. After the knitting of the welts has started the shaft 172 is turned, manually or automatically, bringing the two clips or holders 170 and welt rod in each section over and down to the position shown in Fig. 5. Here it may bear down upon the fabric, preferably with a spring to pull it down, until it comes into the path of forward retraction of the hooks 39^a on the tensioning straps 40. In their forward movements, as the fabric lengthens, the hooks 39^a thus engage the rod ends, still held in the clips or holders 170. The continued forward pull causes the rod to snap out of the clips or holders and cooperate with the straps 40. Thus this time consuming operation is readily and expeditiously performed.

The general operation may now be reviewed, with reference both to the diagrams showing successive positions, and to the mechanism, more especially as shown in Figs. 6, 7 and 8. The operation will be described more particularly with regard to the mechanical actions upon the welt bar 38, giving it the slight side-stepping movements, the rearward advance and return, the lifting and lowering, and the bodily tilting; all of these taking part in the motions shown in the diagrams.

Following initial position A, and after an initial loop course x has been laid, the welt bar 38 and its carriages 15 are moved far rearwardly, bringing the hooks to position B. This rearward movement is effected with the rockframe, carriages and welt bar at their lowest level, as in Fig. 8; this low level being due to the lowered position of the cams 108 on rear shaft 109, under control of the main shaft cam 54. The rearward movement is effected from the other main shaft cam 55 acting through the linkage 148-149 to slide forwardly the rack 141 and thus turn the shaft 105 and with it the two wheels 120, in a direction to thrust rearwardly the two steel strips 11, as best seen in Figs. 3 and 4, these, at their rearward ends, being connected to the carriages 15 upon the cradles 14 of which the welt bar is resiliently mounted.

During the advancing rearward movement of carriages and welt bar, the cam surface 162 of cam plate 160, on the lefthand carriage, comes into play, being at the same level with its fixed-position roller 164, see Figs. 6 and 8, so that before the parts reach their rearmost position B in this section, the cam surface causes a rightward thrust on the carriage and welt bar, proper to position the welt hooks between the planes of the needles. This rightward thrust or adjust-

ment operates to take up the slack indicated by the gap 134 between collar 133 on the shaft 105 and adjacent bracket 51. If the gap should not be sufficient the thrust may then strain slightly the intermediate parts, or take up other play, so that the rightward thrust terminates with the roller 164 upon the cam surface 162. These parts having been machined with precise accuracy, it follows that the positioning of the welt bar for the initial taking of loops, is exactly performed. As the cam plate 160 with its surface 162 is an open cam it is herein arranged that the thrust of the parts can not exceed the desired movement, and this is brought about by the engagement of the righthand contact roller 166 upon the general area or surface of the righthand cam plate 161. Fig. 8 well shows how the two carriages 15, 15, bridged by the welt bar, are positively positioned by the cam surface on the left cam plate cooperating with the low or general area of the righthand cam plate; and it may now be seen that later on, when the carriages are at a higher level the opposite positive action will take place, the cam surface 163 at the right then cooperating with the contact roller 166 while the roller 164 at the left runs on the general area of the lefthand cam plate, thus positively positioning the carriages and welt bar with the welt hooks exactly in the planes of the respective needles.

The next step brings the parts to position C, as previously explained, a forward shift of the needles slipping the loops off from the sinkers and on to the welt hooks. The welt bar is then drawn resiliently forward, holding the loop course, while the knitting of the welt proceeds. It will be understood that the cam 55 at this stage releases its connections to the carriages and welt bar, due to the slot in link 148, so that they are free to be moved forward, the tension cable 136 now coming into play to turn resiliently the shaft 105 in a direction to give the forward tension to the lengthening fabric, continuing until the carriages come to a stop at their most forward position shown in Figs. 1 and 4. Before this time the welt rod 39 is laid in upon the fabric and hitched to the tension straps, for example by the clips or holders 170 already described, so that the pull thereof on the welt fabric may replace the pull exerted through the weltbar, as a continued length of welt fabric is knitted, until the full desired length is attained. This carries the operation to position D, at which the fast or knitting motion or cycle of operation is suspended.

When the working or knitting cycle is thus interrupted, at the conclusion of knitting the welt, the changes are made to transform the action to the already described welt-transferring motion or cycle, which may be the same as the well-known narrowing cycle or action so far as regards the movements of needles, sinkers and knockovers, thus obviating the need of a third kind of cycle. This shift involves a lengthwise shift of the main cam shaft 53, and its slowing down from say sixty to twelve turns per minute, a new set of operating cams coming into play to work the needles, sinkers and knockovers; and at this time the controlled rod 118 is shifted to render operative the special cams 54 and 55 on the shaft 53, which cams afford the necessary weltbar movements, as described, for the transfer of the first loop course x back to the needles. The remaining actions may therefore take place during a single rotation of the cam shaft.

For the transfer operations the welt bar ad-

vances rearwardly again. The weltbar and hooks may move rearwardly from position D as far as position E without either rise or tilt; but during the continued rearward advance the other welt bar movements come into effect. By this time the lug 92 of the push bar 80 has advanced to the relatively fixed stop flange or contact 94, terminating the rearward motion of the push bar. The roller 89 on rocklever 88 has come into substantial contact with the contact piece or shoulder 95 on the yielding shank 96, slidable on the rocker member 100. The welt bar oscillation thereupon, having left the control of lug or contact 91, comes under control of the contact piece or shoulder 95, assisted by the cam finger 69, which by this time is substantially in contact with the press-edge 29.

The weltbar tilting movements result from the further rearward movement of the parts, beyond position E, which movement also brings about the side-stepping of the welt bar to bring the hooks into the planes of the needles. The accompanying lift of the rockframe, consisting of the rocker members 100 and carriages 75, is caused by cams 108 on shaft 109, under main-shaft control; the extent of lift being clear by comparing the full line and dotted line positions in Fig. 7. This lift is sufficient to raise the cam surface 163 on the righthand cam plate 161 up to the level of the contact roller 166, rendering the cam surface 163 operative; at the same time raising the lefthand cam surface 162 above its roller 164, rendering the cam surface inoperative at that side. This rise takes place before the cam plates reach their contact rollers, so that during the continued rearward movement the carriages and weltbar will be thrust leftwardly into exact position, as already explained, for the welt hooks to move thereafter in the planes of the needles. The cam surface 163 may be of short horizontal length as shown, since the contact roller need not pass off from its front shoulder. The cam surface is of substantial vertical width, permitting minor lifting or lowering movements, to change the level of the welt bar as indicated in the diagrams between positions F and M. These lifting and lowering movements conform with the diagram positions and are dependent on the contour of the cam 54, which may be designed accordingly.

The tilting of the welt bar need not commence until beyond position E, when the rise, the rearward shift, and the tilt occur simultaneously to give the resultant movements indicated by positions F, G etc. The position of the parts at stage E having been described, the tilting movements therebeyond may be described as follows. As the carriages and welt bar move rearwardly the contact piece or shoulder 95 exerts a frontward pressure on the stud 89, which operates through rocklever 88 and link 87 to tilt upwardly and rearwardly the welt bar about its pivot studs 68. About the same time, or preferably slightly in advance, the finger 69 is cammed downwardly to ensure the start of the tilting; and the tension of the fabric assists the tilting by its pull on the hook shanks. The welt bar and hooks are thus progressively tilted over in the manner indicated by positions F, G and H. The hooks are thus brought to the vertical position H, having been hurdled over the tops of the needles and brought down vertically behind them, in preparation for loop transfer.

The resilient mounting of the shank of the contact piece or shoulder 95 on the rocker mem-

ber 100 permits it to yield as necessary when the welt bar is subjected to subsequent reverse tilting movement by the action of the needles, for instance at position I, wherein the needles have pressed rearwardly on the hooks, the needle beards in the grooves of the hooks, thus tilting the hooks and welt bar in a manner to stretch the spring 98 which draws the contact piece or shoulder 95 toward its normal position. The needles are now coupled to the welt hooks and the parts are in readiness for the actual loop transfer.

At this point in the action the hooks rise slightly, but the needles to a further extent, to position J, the needles thus accurately entering the initial loops α on the hooks. The fabric and loops were held down, not merely by the welt hook shoulders, but by the knockover hooks which, at position I, had come frontwardly to engage the fabric and yarn. Without such knockovers the loops could still be held down by the sinkers. The first stage of transfer has thus been accomplished. Now, through the loops, which engage both the hooks and needles, the needles continue to control the tilting movements of the hooks, the frontward shift of the needles to position K tilting the hooks in the manner shown, against the resistance of spring 98. In the meanwhile the welt bar and hooks have been lifted extensively by cams 108 to position K, so that the hook ends of the hooks are now brought up to the loops which surround the hook shanks. The lift is applied to some excess so that the carriages 75 have to tilt or heel-up on their shoes 76, tensioning the springs 79, and thus maintaining a desirable upward tension on the loops α , stretched between the welt hooks and the hooks of the knockovers. At position L the needles have again moved slightly rearward, within the loops extending between the welt hooks and the knockovers, the needle beards occupying the loops.

The movements of extracting the hooks from the loops and fabrics may now commence. The weltbar is now shifted rearwardly to its rear limit, this action also tilting the hooks over to their limit of tilting movement, as shown in position M of Figs. 17 and 17^a, shown also in dotted lines in Fig. 7. The tension of the fabric cooperates with the thrust of contact piece or shoulder 95 in this action. It should be noted that in this and subsequent movements the loops, while held at length, are not unduly distended or strained, since the tips of the welt hooks are never lifted as high as the apexes of the needles. Although the hooks are working in the planes of the needles they are able to pass through to the front in the manner indicated in Fig. 16^a, which is a greatly exaggerated front view. The tips and apexes are quite thin and are rounded, so that there is no difficulty in the hook tips brushing past the needle apexes, with very slight deflection, and without conflict or damage.

The described movement from position L to position M carries the hook tips partway beyond the needle apexes. The bent extremity of each hook is substantially horizontal. From position M the carriages and weltbar are shifted frontwardly, the hooks easily extracting themselves from the loops. The frontward retraction of the welt bar is thence continued through positions N, O and P back to original position A. At the commencement of this retraction the contact piece 95 operates, as Fig. 7 shows, to hold the

weltbar in its extremely back-tilted position, but this influence continues only for the short extent of travel between the dotted and full line positions of contact piece or shoulder 95 in Fig. 7, it being stopped by clip 97 at its full line position. During the remainder of the forward retraction the tilting comes again under the control of the rear lug or contact 91 of the push bar 90, which thereupon acts through the parts 89, 88 and 87 to restore progressively the welt bar and hooks through their positions O and P to initial position A.

Means are provided to ensure that the weltbar will tilt to its initial position, resting in the cradle in the manner shown in Fig. 7, full lines. If this were prevented due to failure or weakness of spring 93 acting through lug or contact 91 and rocklever 88, or due to binding action anywhere it would interfere with the hooking-up action on the next knitted stocking. This is taken care of by the front contact lug 92 coming against the front clip 97^a on each of the big rocklevers 100, which ensures the complete rearward shift of the pushbar in its carriage and the restoration of the weltbar to initial position. The action is positive. The clips 97^a in fact determined the final position of forward retraction of the carriages, as Fig. 4 plainly shows, the contact lugs 92 being confined between the clips and the carriages. The welt forming parts remain in this, or position A, until, after the product is completed, they must come again into action as at position B for the start of the next product.

There have thus been described a method and a means for the forming of welts in straight knitting machines which embody the principles of the present invention and attain the objects thereof; and since various matters of operation, combination, arrangement and form may be modified without departing from the novel principles, it is not intended to limit the invention thereto except to the extent set forth in the appended claims.

What is claimed is:

1. For forming welts in a flat knitting machine each knitting section of which has its needle bank and cooperating instruments, the combination therewith of a weltbar having a bank of welt hooks, carriages on which the weltbar is mounted to receive tilting movements or oscillation in reverse directions, carriers or rocklevers on which the carriages are mounted to receive advancing and retracting movements, said carriers being mounted to receive lifting and lowering movements, and an adjusting or cam means in each knitting section operable to side-step the weltbar during an earlier or loop-receiving stage of welt formation for adjusting the welt hooks into exact midspace positions between the needle planes, and to side-step reversely the weltbar during a later or loop-delivering stage for adjusting the welt hooks exactly into the planes of the needles.

2. The combination as in claim 1 and wherein in the side-step adjusting means for the weltbar is caused to operate by reason of the advancing movement of the carriages.

3. The combination as in claim 1 and wherein the side-step adjusting means for the weltbar is caused to operate by reason of the advancing shift of the weltbar through a cam-and-follower device, one element of which is in exact fixed position and the other element connected to the weltbar or a carriage.

4. The combination as in claim 1 and wherein are automatic or self-acting connections for causing the said tilting, advancing and lifting and reverse movements of the weltbar first, for receiving initial loops from the needles and later for transferring such loops back to the needles, substantially in the manner disclosed.

5. The combination as in claim 1 and wherein are automatic or self-acting connections for causing the said tilting, advancing and lifting and reverse movements of the weltbar first, for receiving initial loops from the needles and later for transferring such loops back to the needles, substantially in the manner disclosed; and self-acting connections for causing the side-step adjusting means to position the weltbar suitably for such loop receiving and transferring operations respectively.

6. For forming welts in a flat knitting machine each knitting section of which has its needle bank and cooperating instruments, the combination therewith of a weltbar having a bank of welt hooks, carriages on which the weltbar is mounted to receive bodily tilting movements in reverse directions, an elevator or weltframe on which the carriages are slidably mounted to receive rearward advancing and forward retracting movements, said elevator being swingingly mounted to receive lifting and lowering movements thereby to lift and lower the carriages and weltbar, and a weltbar lateral adjusting means in each knitting section operable to side-step the weltbar during the loop-receiving stage of welt formation for adjusting the welt hooks into midspace positions between the needle planes, and to side-step reversely the weltbar during the loop-transferring stage for adjusting the welt hooks into the planes of the needles.

7. The combination as in claim 6 and wherein the swinging elevator comprises side arms forming ways for the sliding of the carriages, with front fulcrum, and having means to swing up and down the rear ends of the arms, consisting in a lifter actuated in timed coordination with the other movements.

8. For forming welts in a flat knitting machine each knitting section of which has its needle bank and cooperating instruments, the combination therewith of a weltbar having a bank of welt hooks, carriages on which the weltbar is mounted to receive bodily tilting movements in reverse directions over the needles, a swinging elevator or rockframe on which the carriages are slidably mounted to receive rearward advancing and forward retracting movements, said elevator having side arms constituting carriage guides, with front fulcrums, and means to cause lifting and lowering movements thereby to lift and lower the carriages and weltbar, and means for sliding said carriages in unison rearwardly and forwardly upon said arms.

9. The combination as in claim 8 and wherein the carriage sliding means comprises one or more stiffly flexible strips or springs, having their rear ends connected to the carriages and their front ends passing around wheels or segments, and their intermediate portions confined to a given path whereby the strips may both push and pull the carriages, said front wheels, and connections to oscillate said wheels to move the carriages.

10. The combination as in claim 8 and wherein both wheels are fast on a rockshaft which is rocked to move the carriages; said rockshaft constituting also the axle or fulcrum for said rockframe side arms.

11. For forming welts in a flat knitting machine each knitting section of which has its needle bank and cooperating instruments, the combination therewith of a weltbar having a bank of welt hooks, carriages on which the weltbar is mounted to receive bodily tilting movements in reverse directions, an elevator or weltframe on which the carriages are mounted to receive rearward advancing and forward retracting movements, said elevator being mounted to receive lifting and lowering movements thereby to lift and lower the carriages and weltbar, and a weltbar side-stepping means in each knitting section operable to cause minute shifting of the weltbar endwise of itself for adjusting the welt hooks into a first or midspace position between the needle planes at an earlier stage, and at a later stage to shift reversely the weltbar for adjusting the welt hooks into a second position in the planes of the needles.

12. The combination as in claim 11 and wherein the side-stepping means comprises complementary cam and follower devices operating by reason of the rearward and forward movements of carriages and weltbar.

13. The combination as in claim 11 and wherein the side-stepping means comprises complementary cam and follower devices operating by reason of the rearward and forward movements of carriages and weltbar, so arranged that when the elevator and carriages are at a low level at the earlier stage the first device acts to thrust the weltbar to its first endwise position, and when at a high level at the later stage the second device acts to thrust the weltbar to its second position.

14. For forming welts in a flat knitting machine each knitting section of which has its bank of needles and cooperating instruments, the combination therewith of a weltbar having a bank of welt hooks, a supporting member, means for moving the supporting member to receive movements towards and away from the needles and lifting and lowering movements relatively to the needles, means mounting the weltbar on the supporting member to receive bodily tilting movements in reverse directions over the needles in coordination with said other movements, and mechanism operating to tilt the welt bar during, and by reason of, the movements of the supporting member towards and away from the needles, said mechanism comprising a rocklever on said member and connected to the welt bar, a contact acting on the rocklever to tilt the welt bar from normal position during movement towards the needles, and a pusher acting to restore the welt bar to normal during movement away from the needles.

15. The combination as in claim 14 and wherein in the mountings and mechanism are yieldingly assembled and relatively arranged to deliver tilting movements substantially as described.

16. The combination of claim 14 and wherein is a supplemental welt bar tilting means comprising a cam finger arranged on the welt bar for movement therewith, and a contact disposed in the path of the welt bar when moving towards the needles, whereby said finger during movement of the welt bar towards the needles will engage the contact causing said finger and welt bar to tilt.

17. For forming welts in a flat knitting machine each knitting section of which has its needle bank and cooperating instruments, the combination therewith of a weltbar having a

bank of welt hooks, carriages on which the ends of the weltbar are pivoted adapting the weltbar to receive bodily tilting movements, an elevator or rockframe on which the carriages are movably mounted to shift rearwardly and forwardly, timed means to cause lifting and lowering elevator movements thereby to lift and lower the carriages and welt bar, timed means for shifting said carriages in unison rearwardly and forwardly upon said elevator thereby to shift the weltbar accordingly, and timed means for tilting the weltbar on its carriages during its other movements.

18. The combination as in claim 17 and wherein in the elevator is a rockframe with front fulcrum and rear means to swing it up and down.

19. The combination as in claim 17 and wherein in the means for tilting the weltbar is a self-acting means operating by reason of the movements of the carriages.

20. The combination as in claim 17 and wherein is a weltbar side-stepping means in each knitting section, each thereof having connections operating to shift the weltbar endwise of its length to bring the welt hooks into needle plane positions for welt transfer and into mid-plane positions for initial hooking up of loops.

21. The combination as in claim 17 and wherein is a weltbar side-stepping means in each knitting section, each thereof having connections operating to shift the weltbar endwise of its length to bring the welt hooks into needle plane positions for welt transfer and into mid-plane positions for initial hooking up of loops; such side-stepping means comprising a self-acting device acting upon a carriage by reason of the shift of the carriage.

22. The combination as in claim 17 and wherein is a front means for retracting forwardly the carriages and weltbar while said carriage-shifting means is idle during the knitting of the welt, and a cushion or spring device included in the connections between said front retracting means and the weltbar to smooth the retraction thereof.

23. In forming welts in a flat knitting machine, each knitting section of which has its bank of needles and cooperating instruments, the combination therewith of a welt bar having a bank of welt hooks, carriages on which the welt bar is mounted to receive bodily tilting movements in reverse directions and an elevator on which the carriages are mounted to receive movements towards and away from the needles, said elevator being mounted to receive lifting and lowering movements thereby to lift and lower the carriages and welt bar, a welt bar side-stepping in each knitting section operable to cause minute shifting of the welt bar endwise of itself for adjusting the welt hooks into a first position between the needle planes at an earlier stage, and at a later stage to shift reversely the welt bar for adjusting the welt hooks into a second position in the planes of the needles, said side-stepping means comprising complementary cam and follower devices operating by reason of the movements of the carriages and welt bar towards the needles and being so arranged that when the elevator and carriages are at a low level at the earlier stage, the first device acts to thrust the welt bar to its first endwise position, and when at a high level at the later stage, the second device acts to thrust the welt bar to its second position, each cam and follower device including a cam plate on a carriage and a fixed

follower, each cam plate having a general face and a cam surface so arranged at different levels that when one follower engages the cam surface of its cam plate, the other follower engages the general area of its cam plate, thus positively positioning the carriages and welt bar endwise at each stage of operation.

24. The method of forming a stocking welt by means of a welt bar having welt hooks on a flat knitting machine provided with a bank of bearded needles and cooperating instrumentalities, comprising: knitting a series of initial welt fabric loops on said needles with the aid of said cooperating instrumentalities; actuating the welt bar to impart to the welt hooks a first movement towards the needles; guiding the welt bar in said first movement toward the needles for so positioning the hooks in relation to the needles that said hooks will pass between the needles to engage the initial loops thereon; knitting the body of the welt fabric on said needles with the aid of the cooperating instrumentalities; actuating the welt bar to move the welt hooks away from the needles after engaging the initial loops and accordingly draw the welt fabric being knitted; actuating the welt bar following the formation of the final loops of the welt fabric to impart to the welt hooks a second movement towards the needles and, simultaneously therewith, actuating the welt bar to impart to the welt hooks a lifting movement whereby to turn the welt fabric and bring the welt hooks on a plane above the needles; actuating the welt bar to move the welt hooks during said second movement towards the needles and said lifting movement to align the welt hooks with the needles; actuating the welt bar to cause the welt hooks to vault over the needles and become positioned in substantial parallel relation to the beard side of the needles preparatory to the transfer to the initial loops back onto the needles; actuating the welt bar to move the welt hooks in coaction with the motion of the needles and cooperating instrumentalities for bringing the initial loops under tension between said instrumentalities and welt hooks for the engagement of said loops by the needles; actuating the welt bar to move the welt hooks for forcing the ends thereof past the needles on the plain side thereof and thus disengaging the initial loops in engagement with the needles; actuating the welt bar to move the welt hooks out of the knitting field; and then knitting a series of loops to unite the initial and final loops of the welt fabric.

25. In a multi-section knitting machine having welt forming mechanism, a device for laying welt rods on the fabrics in the several knitting sections comprising: welt rod retaining spring means within each knitting section adapted to engage the welt rod for use therein and movable to operative position for suspending said welt rod over the corresponding fabric; and supporting and positioning means for said welt rod retaining spring means and including a member extending throughout the several knitting sections for moving all of said welt rod retaining spring means simultaneously to operative position.

26. In a multi-section knitting machine having welt forming mechanism, the combination with tensioning hook carrying straps mounted in each knitting section for travel therein, of a device for laying welt rods on the fabrics in the several knitting sections comprising: welt rod retaining spring means within each knitting sec-

tion adapted to engage the welt rod for use therein and movable to operative position for suspending said welt rod over the corresponding fabric in the path of the hooks on the travelling straps, whereby said hooks may snap the associated welt rod out of its retaining spring means; and supporting and positioning means for said welt rod retaining spring means and including a member extending throughout the several knitting sections for moving all of said welt rod retaining means simultaneously to operative position.

27. An automatic welt turning attachment comprising, in combination with a bank of bearded needles and cooperating instrumentalities in a flat knitting machine: a welt bar having welt hooks; means operable for actuating the welt bar to impart to the welt hooks a first movement towards the needles; means operable to guide the welt bar in said first movement towards the needles whereby to so position the welt hooks in relation to the needles that said hooks will pass between the needles to engage the initial loops thereon; means operable to actuate the welt bar for moving the welt hooks away from the needles after engaging the initial loops and accordingly drawing the welt fabric being knitted on said needles with the aid of the cooperating instrumentalities; means operable to actuate the welt bar following the formation of the final loops of the welt fabric for imparting to the welt hooks a second movement towards the needles and, simultaneously therewith, a lifting movement whereby to turn the welt fabric and bring the welt hooks on a plane above the needles; means operable to actuate the welt bar to move the welt hooks during said second movement towards the needles and said lifting movement to align the welt hooks with the needles; means operable to actuate the welt bar to cause the welt hooks to vault over the needles and become positioned in substantially a parallel plane in relation to the beard side of the needles preparatory to the transfer of the initial loops back onto the needles; means operable to actuate the welt bar for moving the welt hooks in coaction with the motion of the needles and cooperating instrumentalities to bring the initial loops under tension between said instrumentalities and welt hooks for the engagement of the loops by the needles; means operable to actuate the welt bar for moving the welt hooks whereby to force the ends of the latter past the plain side of the needles and thus disengage the initial loops in engagement with the needles; and means operable to actuate the welt bar for moving the welt hooks out of the knitting field.

28. In a flat knitting machine, the combination with the main cam shaft and the bank of bearded needles operated thereby: of a bank of welt hooks; mechanism operating to move said bank of welt hooks in a combined rectilinear path towards the needles and a curvilinear path over the needles to bring the welt hooks into engagement with the bearded side of said needles; and means operatively connecting said mechanism to the main cam shaft whereby said mechanism is operated in timed relation with the operation of said bank of needles.

29. In a flat knitting machine, the combination with the main cam shaft and the bank of bearded needles operated thereby: of a bank of welt hooks; mechanism operating to move said bank of welt hooks in a combined continuous rectilinear horizontal path towards the needles

and a curvilinear vertical path over and behind the needles on the bearded side thereof; and means operatively connecting said mechanism to the main cam shaft whereby said mechanism is operated in timed relation with the operation of said bank of needles.

30. In a flat knitting machine, the combination with the main cam shaft and the bank of bearded needles actuated thereby: of a bank of welt hooks; mechanism operable to actuate said welt hooks in a combined rectilinear path towards said needles and a curvilinear path over the needles to bring the welt hooks into engagement with the bearded side of said needles; and cam means on the main cam shaft for operating said mechanism to actuate the welt hooks in timed relation with the actuation of said needles by the main cam shaft.

31. In a flat knitting machine, the combination with the main cam shaft and the bank of bearded needles actuated thereby: of a bank of welt hooks; mechanism operable to actuate said welt hooks in a combined continuous rectilinear horizontal path towards said needles and a curvilinear vertical path over and behind the needles on the bearded side thereof; and cam means on the main cam shaft for operating said mechanism to actuate the welt hooks in timed relation with the actuation of said needles by the main cam shaft.

32. In a flat knitting machine, the combination with the main cam shaft, the bank of bearded needles, a set of knitting cams on the main cam shaft to actuate said needles during the knitting cycle of the machine, and a set of narrowing cams on the main cam shaft to actuate said needles during the narrowing cycle of the machine: of a bank of welt hooks; a mechanism operable to actuate said welt hooks in a combined rectilinear path towards the needles and a curvilinear path to bring the welt hooks into engagement with the bearded side of said needles; and cam means on the main cam shaft for operating said mechanism to actuate the welt hooks in timed relation with the actuation of said needles during the narrowing cycle of the machine by said set of narrowing cams on said main cam shaft.

33. In a flat knitting machine, the combination with the main cam shaft, the bank of bearded needles, a set of knitting cams on the main cam shaft to actuate said needles during the knitting cycle of the machine, and a set of narrowing cams on the main cam shaft to actuate said needles during the narrowing cycle of the machine: of a bank of welt hooks; a mechanism operable to actuate said welt hooks in a combined rectilinear path towards the needles and a curvilinear path over and behind the needles on the bearded side thereof; and cam means on the main cam shaft for operating said mechanism to actuate the welt hooks in timed relation with the actuation of said needles during the narrowing cycle of the machine by said set of narrowing cams on said main cam shaft.

34. In a flat knitting machine having a bank of bearded needles and a main cam shaft for actuating said needles, a welt forming attachment comprising: a bank of welt hooks; mechanism operatively associated with said hooks to actuate the same in a rectilinear path towards said needles and in a curvilinear path to bring the welt hooks into engagement with the bearded side of said needles; and cam means on the main cam shaft operatively associated with said mechanism

for operating the same to actuate the welt hooks in timed relation with the actuation of said needles by the main cam shaft.

35. In a flat knitting machine having a bank of bearded needles and a main cam shaft for actuating said needles, a welt forming attachment comprising: a bank of welt hooks; mechanism operatively associated with said hooks to actuate the same in a rectilinear path towards said needles and in a curvilinear path over and behind said needles on the bearded side thereof; and cam means on the main cam shaft operatively associated with said mechanism for operating the same to actuate the welt hooks in timed relation with the actuation of said needles by the main cam shaft.

36. In a flat knitting machine having a bank of bearded needles and a main cam shaft for actuating said needles, a welt forming attachment comprising: a bank of welt hooks; and mechanism associated with the main cam shaft and connected to said hooks to actuate the same in a rectilinear path towards said needles and in a curvilinear path to bring the welt hooks into engagement with the bearded side of said needles in timed relation with the actuation of said needles by the main cam shaft.

37. In a flat knitting machine having a bank of bearded needles and a main cam shaft for actuating said needles, a welt forming attachment comprising: a bank of welt hooks; and mechanism operatively associated with the main cam shaft and connected to said hooks to actuate the same in a rectilinear path towards said needles and in a curvilinear path over and behind the needles on the bearded side thereof in timed relation with the actuation of said needles by the main cam shaft.

38. In a flat knitting machine, a needle bar having a bank of bearded needles; a main cam shaft controlling the actuation of said needles; a welt bar having welt hooks adapted for cooperation with the needles on the needle bar; mechanism operable to actuate the welt bar in a rectilinear motion towards the needles and in a curvilinear motion to bring the welt hooks on the welt bar into engagement with the bearded side of the needles on the needle bar; and means establishing a direct connection between the main cam shaft and said mechanism for operating the latter to actuate the welt bar in timed relation with the actuation of the needle bar.

39. In a flat knitting machine, a needle bar having a bank of bearded needles; a main cam shaft controlling the actuation of said needles; a welt bar having welt hooks adapted for cooperation with the needles on the needle bar; mechanism operable to actuate the welt bar in a rectilinear motion towards the needles and in a curvilinear motion over and behind said needles on the bearded side thereof; and means establishing a direct connection between the main cam shaft and said mechanism for operating the latter to actuate the welt bar in timed relation with the actuation of the needle bar.

40. In a flat knitting machine, a needle bar having a bank of bearded needles; a main cam shaft; cam means on said shaft for actuating said needle bar; a welt bar having welt hooks adapted for cooperation with the needles of the needle bar; mechanism operable to actuate the welt bar in a rectilinear motion towards the needles of the needle bar and in a curvilinear motion to bring the welt hooks on the welt bar into engagement with the bearded side of the needles on the needle bar.

dle bar; and other cam means on the main cam shaft, said other cam means being operatively associated with said mechanism and acting thereon for operating the same to actuate the welt bar in timed relation with the actuation of the needle bar by said first mentioned cam means on the main cam shaft.

41. In a flat knitting machine, a needle bar having a bank of bearded needles; a main cam shaft; cam means on said shaft for actuating said needle bar; a welt bar having welt hooks adapted for cooperation with the needles of the needle bar; mechanism operable to actuate the welt bar in a rectilinear motion towards the needles of the needle bar and in a curvilinear motion over and behind said needles on the bearded side thereof and other cam means on the main cam shaft, said other means being operatively associated with said mechanism and acting thereon for operating the same to actuate the welt bar in timed relation with the actuation of the needle bar by said first mentioned cam means on the main cam shaft.

42. In combination with the bank of needles and main cam shaft of a flat knitting machine: a welt bar having a bank of welt hooks; carriers on which the welt bar is mounted to receive bodily tilting movements in reverse directions over the needles; swinging arms on which the carriers are slidably mounted to receive sliding movements towards and away from the needles, said arms being mounted to receive lifting and lowering movements; means operated by the main cam shaft to cause lifting and lowering movements of the arms whereby to lift and lower the carriers of the welt bar; and means also operated by the main cam shaft for sliding the carriers in unison upon said arms.

43. In combination with the bank of bearded needles of a flat knitting machine, a welt turning mechanism comprising: a welt bar; carrier devices, one for each end of the welt bar; and mechanism operable for positive action on the welt bar carrier devices for positively moving the welt bar in a rectilinear path towards and away from the needles during and for the picking-up phase of the initial course of loops and the knitting of the welt fabric on the knitting machine, and for positively moving the welt bar in a horizontal side-step and curvilinear motion towards and behind the needles to engage said hooks with the bearded side of the needles for and during the transfer phase of the initial course of loops of the welt.

44. In a flat knitting machine having a plurality of knitting sections and provided with a main cam shaft: a welt bar for each knitting section having a bank of welt hooks; carriers on which the welt bars are mounted to receive tilting movements in reverse directions; supports on which the carriers are mounted to receive sliding movements towards and away from the needles, said supports being mounted to receive lifting and lowering movements; mechanism operated by the main cam shaft for sliding the carriers on their supports towards the needles; mechanism also operated by the main cam shaft for lifting and lowering said supports; and means in each knitting section of the knitting machine operable to side-step the welt bar during the loop receiving stage of the welt formation for adjusting the welt hooks in mid space positions between the needle planes, and to side-step reversely the welt bar during the loop delivering stage for adjusting the welt hooks into the planes of the needles.

45. In combination with the bank of needles in each knitting section, and the main cam shaft of a flat knitting machine: a welt bar for each section having a bank of welt hooks; carriers on which the welt bars are mounted to receive tilting movements in reverse directions; supports on which the carriers are mounted to receive sliding movements towards and away from the needles, said supports being mounted to receive lifting and lowering movements; mechanism operated by the main cam shaft for sliding the carriers on their supports towards the needles; mechanism also operated by the main cam shaft for lifting and lowering said supports; and welt bar laterally adjusting means in each knitting section of the knitting machine operable to side-step the welt bar during the loop receiving stage of the welt formation for adjusting the welt hooks in mid space positions between the needle planes, and to side-step reversely the welt bar during the loop delivering stage for adjusting the welt hooks into the planes of the needles.

46. In a flat knitting machine, the combination with the main cam shaft and a bank of needles operated thereby: of a bank of welt hooks; mechanism operating to move said bank of welt hooks in a horizontal rectilinear path towards and away from the needles; means cofunctioning with said mechanism for moving the welt hooks in a curvilinear path over and behind the needles as a continuation of the movement in a horizontal rectilinear path and, simultaneously therewith, variably changing the angular relationship of the hooks with the needles; and means operatively connecting said mechanism and means to the main cam shaft whereby said mechanism and means are operated in timed relation with the operation of said bank of needles.

47. In a flat knitting machine, the combination with the main cam shaft and a bank of bearded needles operated thereby: of a bank of welt hooks; mechanism operating to move said bank of welt hooks in a horizontal rectilinear path towards and away from the needles; means co-functioning with said mechanism for moving the welt hooks in a curvilinear path over and behind the needles as a continuation of the movement in a horizontal rectilinear path and, simultaneously therewith, variably changing the angular relationship of the hooks with the needles; and cam means on the main cam shaft for operating said mechanism and means to actuate the welt hooks in timed relation with the operation of said needles by the main cam shaft.

48. In a flat knitting machine, the combination with the main cam shaft and the bank of bearded needles operated thereby: of a bank of welt hooks adapted to engage and remove loops from the needles and subsequently return said loops to the needles; mechanism operating to move said welt hooks in a rectilinear horizontal path towards and away from said needles to engage and remove the loops therefrom, then in a combined rectilinear path towards the needles and curvilinear path over and behind the needles to position the welt hooks on the bearded side of the needles thereby returning the loops to the needles, then in a curvilinear path behind the needles towards the bearded side thereof to disengage said hooks from the loops returned on the needles, then in a reverse curvilinear path over the needles to place the disengaged welt hooks in front of said needles, and finally in a recti-

linear path away from the needles; and means operatively connecting said mechanism to the main cam shaft whereby said mechanism is operated in timed relation with the operation of said bank of needles.

49. In a flat knitting machine, the combination with the main cam shaft and the bank of bearded needles operated thereby: of a bank of welt hooks adapted to engage and remove loops from the needles and subsequently return said loops to the needles; mechanism operating to move said welt hooks in a rectilinear horizontal path towards and away from said needles to engage and remove the loops therefrom, then in a combined rectilinear path towards the needles and curvilinear path over and behind the needles to position the welt hooks on the bearded side of the needles thereby returning the loops to the needles, then in a curvilinear path behind the needles toward the bearded side thereof to disengage said hooks from the loops returned on the needles, then in a reverse curvilinear path over the needles to place the disengaged welt hooks in front of said needles, and finally in a rectilinear path away from the needles; and cam means on the main cam shaft for operating said mechanism to move the welt hooks in timed relation with the operation of said needles on the main cam shaft.

50. In a method of forming welts on full-fashioned knitting machines by means of welt hooks adapted for cooperative relative movements with the bearded needles of the knitting machine, the steps of: manually moving the welt hooks into engagement with a set of knitted loops; mechanically moving the welt hooks away from the needles and knitting lengths of fabrics; manually placing the welt rods relative to the knitted fabrics; mechanically moving the welt rods into engagement with the fabrics and tensioning the same; and mechanically moving the welt hooks in a continuous rectilinear path towards the needles and a curvilinear path over the needles into engagement with the beards of the needles to deposit the loops on said needles.

51. In a method of turning welts on a full-fashioned knitting machine through the cooperative functions of needles and of welt hooks having shanks longitudinally engageable at one side with the associated needles and terminating with hook ends extending from the other side, and adapted to engage and thrust loops away from, and subsequently deposit said loops onto, the needles, the steps of: moving the welt hooks to bring their shanks into engagement with the associated needles for depositing the loops thereonto; and then moving the welt hooks to displace the hook ends in a curvilinear path traversing the longitudinal plane of the needles and thus dispose said hook ends to extend at right angles to the lengths of the needles during said movement, whereby to slide out of the loops deposited on the needles.

52. In a method of turning welts on a full-fashioned knitting machine through the cooperative functions of spring beard needles and of welt hooks having shanks longitudinally engageable at one side with the associated needles and terminating with hook ends extending from the other side and adapted to engage and thrust loops away from, and subsequently deposit said loops onto, the needles, the steps of: moving the welt hooks to bring their shanks into engagement with the beard side of the associated needles for depositing the loops thereonto; and then moving the welt hooks to displace the hook ends in a

curvilinear path traversing the longitudinal plane of the needles causing said welt hook ends to cross from the beard side to the plain side thereof and thus dispose said hook ends to extend at right angles to the lengths of the needles during said movement, whereby to slide out of the loops deposited on the needles.

53. In a method of turning welts on a full-fashioned knitting machine through the cooperative functions of vertically extending spring beard needles and of welt hooks having shanks longitudinally engageable at one side with the associated needles and terminating with hook ends extending from the other side and adapted to engage and thrust loops away from, and subsequently deposit said loops onto, the needles, the steps of: moving the welt hooks to bring their shanks into engagement with the beard side of the associated needles for depositing the loops thereonto; and then moving the welt hooks to displace the hook ends in a curvilinear path traversing the longitudinal plane of the needles causing said welt hook ends to cross from the beard side to the plain side thereof and thus dispose said hook ends to extend horizontally with respect to the lengths of the needles during said movement, whereby to slide out of the loops deposited on the needles.

54. In a welt turning attachment for flat full-fashioned knitting machines, the combination with a welt bar of a mechanism for imparting reciprocating movements to the welt bar comprising: welt bar carrying means; take-up means mounted for reversible rotating movements; a flexible strip having one end portion attached to the take-up means and the other end portion connected to the welt bar carrying means; and means engaging and guiding the intermediate portion of said strip whereby the latter may push the welt bar carrying means with the rotation of the take-up means in one direction, and pull said welt bar carrying means with the rotation of said take-up means in the other direction.

55. In a welt turning attachment for flat full-fashioned knitting machines having a plurality of knitting sections, the combination with a welt bar for each knitting section of a mechanism for imparting simultaneous reciprocating movements to the welt bar comprising: a carriage for each end of the welt bar of each knitting section; a shaft extending throughout the plurality of knitting sections and mounted for reversible rotating movements; a wheel for each carriage and carried on said shaft for rotation therewith; a flexible strip for each carriage and wheel and having its opposite end portions respectively connected to the associated carriage and wheel; and a channel enclosing and guiding the intermediate portion of each strip whereby said strips may simultaneously push the welt bar carriages with rotation of the take-up means in one direction, and pull said welt bar carriages with the rotation of said take-up means in the other direction.

56. In a multi section knitting machine having 65 welt forming mechanism, a device for laying welt rods on the fabrics in the several knitting sections comprising: a shaft extending throughout the several knitting sections and mounted for reversible rotating movements; pairs of arms fixed on said shaft to extend at right angles thereto, one pair of arms being disposed within the confines of each knitting section and each arm terminating with welt rod engaging spring means whereby, upon rotation of the shaft in one direction, the spring means of said arms may be lo-

cated simultaneously in position to place the welt rod in retaining engagement therewith, and upon rotation of the shaft in the other direction, the spring means on said arms may be located simultaneously in position for releasably suspending the engaged welt rods over the fabrics being knitted in the corresponding knitting sections of the machine.

57. In a multi section knitting machine having welt forming mechanism, the combination with tensioning hook carrying straps mounted in each knitting section for travel therein of a device for laying welt rods on the fabrics in the several knitting sections, comprising: a shaft extending throughout the several knitting sections and mounted for reversible rotating movements; pairs of arms fixed on said shaft to extend at right angles thereto, one pair of arms being disposed within the confines of each knitting section and each arm terminating with welt rod engaging spring means whereby, upon rotation of the shaft in one direction, the spring means of said arms may be located simultaneously in position to place the welt rod in retaining engagement therewith, and upon rotation of the shaft in the other direction, the spring means on said arms may be located simultaneously in position for releasably suspending the engaged welt rods over the fabrics being knitted in the corresponding knitting sections of the machine and in the path of the hooks of the travelling straps to snap the associated welt rods out of their retaining spring means.

58. In a welt forming attachment for knitting machines of the character described: a welt bar; carrier devices, one for each end of the welt bar; a mechanism operable for moving said welt bar carrier devices to draw and turn the welt fabric, said mechanism including movement imparting means, lengths of flexible material establishing connections between said movement imparting means and welt bar carrier devices for pulling and pushing the latter, and rigid guide members associated with said lengths of flexible material for guiding the same in a predetermined direction in their pulling and pushing of the welt bar carrier devices.

59. In a flat knitting machine, the combination with bearded needles, knockover bits, and sinkers: of a welt bar having welt hooks; means for imparting to the welt bar a rectilinear, horizontal forward movement to advance the welt hooks towards the needles, for bringing said hooks from an inactive to an active position; means for guiding the welt bar during a part of said movement for so positioning the welt hooks in relation to the needles that during the continued rectilinear forward movement of the welt bar, said hooks will pass between the needles in line with the sinkers at a point between the sinkers and knockover bits to engage the initial sinker loops when they are cast off said sinkers; means for imparting to the welt bar a rectilinear horizontal backward movement to retract the welt hooks away from the needles after engaging the sinker loops and, accordingly, draw the welt fabric under tension while being knitted on said needles; means for imparting to the welt bar a rectilinear slanting upward movement towards the needles to turn the welt fabric and bring the welt hooks on a plane above the heads of the needles; means for imparting to the welt bar a rectilinear horizontal sideway movement to side-step the welt hooks for their alignment with the needles; means for imparting to the welt bar a curvilinear

substantially forward movement towards the needles to cause vaulting of the welt hooks over the needles and continuing in a curvilinear substantially downward movement to place said welt hooks behind the needles on the beard side thereof preparatory to the transfer of the initial sinker loops back onto the needles; means for imparting to the welt bar a rectilinear substantially downward movement to bring the initial loops adjacent to the needle heads at a point between the knockover bits and the sinkers to place said loops in position for engagement by the needles; means for imparting to the welt bar a substantially rectilinear vertical upward movement cooperating with the needle motion for eventually bringing the loops under tension between the sinkers, and welt hooks; means for imparting to the welt bar a combined thrust forward movement and slightly vertical downward movement after the initial sinker loops have been engaged by the needles, said forward movement bringing the welt hook ends into an approximate horizontal position preparatory to unhooking, and said downward movement relieving the tension of the initial sinker loops for the instantaneous disengagement of said hook ends from said loops; means for imparting to the welt bar a rectilinear horizontal backward movement away from the needles to move the welt hooks out of the knitting field; means for imparting to the welt bar a curvilinear tilting backward movement away from the needles to place the welt hooks in their normal position in a substantially horizontal plane; and means for imparting to the welt bar a rectilinear horizontal backward movement away from the needles to return the welt hooks to their original inactive position.

60. A combined welt turning and take-up attachment for flat knitting machines comprising, in combination with a welt bar and a welt rod: a welt bar mechanism and a welt rod mechanism; said welt bar mechanism including a carrier device for each end of the welt bar, movement imparting means having a take-up shaft, yieldable means establishing connections between the take-up shaft and connected to said carrier devices, and means engageable with the carrier devices to impart tilting swinging movements to the welt bar; said welt rod mechanism including a welt rod engaging element for each end of the welt rod, movement imparting means having a wareroller shaft, and yieldable means establishing connections between the wareroller shaft and connected to said welt rod engaging elements.

61. In a full-fashioned hosiery knitting machine, a welt forming and turning mechanism comprising: a welt bar; carrying means for the welt bar adapted to impart welt forming and turning movements thereto, said means including a support rigidly connected to the welt bar, a cradle-shaped member adapted to form a bed for the welt bar and mounted for reciprocating movement, an extension formed with said member and to which is hinged the welt bar support, a lever pivoted at its intermediate portion to said member, a link having one of its ends pivoted to one end of said lever and having the other of its ends pivoted to the welt bar support at a point adjacent the hinged connection of the latter to said member, the other end portion of said lever carrying a laterally projecting stud and a stop disposed to engage said stud during the reciprocating movement of said member in one direction for

swinging the support to move the welt bar out of the bed formed by said member.

62. In a full-fashioned hosiery knitting machine, a welt forming and turning mechanism comprising: a welt bar; carrying means for the welt bar adapted to impart welt forming and turning movements thereto, said means including a support rigidly connected to the welt bar and provided with a longitudinally extending projection, a cradle-shaped member adapted to form a bed for the welt bar and mounted for reciprocating movement, an extension formed with said member and to which is hinged the welt bar support at a point between its welt bar connected portion and longitudinally extended projection, a lever pivoted at its intermediate portion to said member, a link having one of its ends pivoted to one end of said lever and having the other of its ends pivoted to the welt bar support at a point adjacent the hinged connection of the latter to the extension of said member, the other end portion of said lever carrying a laterally projecting stud and a stop disposed to engage said stud during the reciprocating movement of said member in one direction for swinging the support to move the welt bar out of the bed formed by said member and to engage the extended projection of the support during the reciprocating movement of said member in the other direction for swinging the support to move the welt bar into its bed.

63. In a full-fashioned hosiery knitting machine, a welt forming and turning mechanism comprising: a welt bar; carrying means for the welt bar adapted to impart welt forming and turning movements thereto, said means including a support rigidly connected to the welt bar, a cradle-shaped member adapted to form a bed for the welt bar and mounted for reciprocating movement, an extension formed with said member and to which is hinged the welt bar support, a lever pivoted at its intermediate portion of said member, a link having one of its ends pivoted to one end of said lever and having the other of its ends pivoted to the welt bar support at a point adjacent the hinged connection of the latter to said member, the other end portion of said lever carrying a laterally projecting stud and a stop mounted for adjustment in the path of movement of the cradle-shaped member disposed to engage said stud during the reciprocating movement of said member in one direction for swinging the support to move the welt bar out of the bed formed by said member.

64. In a flat knitting machine, in combination: a bank of knitting needles; a welt bar; means for movably supporting the welt bar; a rotatable shaft; and flexible strips connected to the welt bar supporting means and having wrapped en-

gagement with said shaft, whereby upon rotating the latter in opposite directions the welt bar is moved towards and away from said bank of needles.

65. In a multi section flat knitting machine, in combination: a bank of needles within each knitting section; a welt bar associated with each bank of needles; means for each welt bar movably supporting the same in relation to its associated bank of needles within the corresponding knitting section; a rotatable shaft common to all knitting sections; yieldable flexible means establishing a direct connection between the welt bar supporting means and the rotatable shaft whereby upon rotation of the latter in opposite directions all the welt bars are moved in unison towards or away from their respective banks of needles; a welt rod associated with each knitting section; a wareroller shaft common to all knitting sections; and means located within each knitting section having elements engageable with the welt rod of the associated knitting section and operatively connected to the wareroller shaft whereby rotation of said wareroller shaft will bring said elements in unison into position for engagement with the welt rods and rotation of said wareroller shaft in another direction will cause said elements to engage the welt rods in unison.

66. In a flat knitting machine: a welt bar; separate carrier devices one for each end of the welt bar; and a mechanism for advancing and retracting the welt bar carrier devices in unison, said mechanism including the welt bar carrier devices in unison, said mechanism including lengths of flexible material attached to the welt bar carrier devices, rigid guide members associated with said lengths of flexible material for guiding the same in a predetermined direction, drums connected with said lengths of flexible material for winding and unwinding the same, a rack device for operating said drums to wind and unwind the lengths of flexible material, and a power driven means for actuating said rack device.

67. In a flat knitting machine, in combination: a bank of knitting needles; a welt bar; means for movably supporting the welt bar; a rotatable shaft; yieldable flexible means establishing a direct connection between the welt bar supporting means and the rotatable shaft, whereby upon rotating the latter in opposite directions the welt bar is moved towards or away from said bank of needles; means whereby said shaft may be rotated manually; and means whereby said shaft may be rotated mechanically by actuation of an operative element of the knitting machine.
